UNITED STATES PATENT OFFICE.

HENRY STEPHEN LAND, OF THE COUNTY OF ESSEX, ENGLAND.

APPARATUS FOR TURNING, SHAPING, AND SCREW-THREADING RODS OR OTHER METAL BLANKS.

1,113,023.

Specification of Letters Patent.

Patented Oct. 6, 1914.

Application filed December 31, 1912. Serial No. 739,508.

To all whom it may concern:

Be it known that I, HENRY STEPHEN LAND, a subject of the King of Great Britain, residing in Essex, England, and whose post-office address is 8 Park View, Old Road, Lee, in the county of Essex, England, engineer, have invented certain new and useful Improvements in Apparatus for Turning, Shaping, and Screw-Threading 5 Rods or other Metal Blanks, of which the following is a specification.

This invention relates to an attachment for lathes whereby rods or other metal blanks may be turned, shaped and screw threaded, and it consists in improvements having for their objects (1) to provide a revoluble support for the metal blanks to be operated upon (2) to insure, by means of an improved construction of ball bearing in the 10 revoluble support, that the blank will be supported and truly centered in the rotating bush or disk constituting this support through which the blank is fed toward the cutting tools, (3) to facilitate the conversion 15 of the attachment for dealing with blanks of different cross sections, by providing detachable centers or bushes for the blank support secured, for example, by a bayonet joint, and (4) to eliminate the disadvantages arising 20 from the fact that in similar existing apparatus the blank has to be fed to the cutters through the opening in the screw-cutting die head, by mounting the latter so that it can be swung laterally clear of the cutting-tool 25 box and locked both in the "off" and in the operative position, thereby reducing the unnecessary projection of the blank from the lathe chuck and also enabling the tool to deal with blanks of larger size for any given 30 size of die head.

The invention is illustrated in the accompanying drawings, wherein—

Figure 1 is an end elevation; Fig. 2 a side elevation; Fig. 3 a longitudinal section; Fig. 4 a plan; Fig. 5 an elevation of the ball bearing for the blank guide or bush; and Fig. 6 a detail view showing the blank guide.

Referring to Figs. 1-3, the apparatus consists essentially of two elements, namely 50 a tool box A and a screw cutting die head B. According to this invention the latter is pivotally mounted upon the tool box head a by means of a pin a' projecting forwardly on a lug on the tool box head, which is also

fitted with a spring-urged latch a^2 , which 55 is adapted to lock the die head in either of two positions, namely with the die head concentric with the tool box as shown in full lines in Figs. 1 and 2 of the drawings, and also with it swung aside upon the pin a' 60 clear of the front face of the tool box head, as shown in dotted lines in Figs. 1 and 2.

The cutting tool holders b , of which there may be any desired number, are slidable longitudinally on guides b' one at each side 65 of the tool box.

In the drawings, at each side of the tool box there are four cutting-tools d and three tool holders b , the two intermediate cutting-tools being mounted in the same holder. 70

The revoluble support in the tool box head through which the blank is fed and by which it is supported is, according to the present invention, fitted with a detachable bush j which is secured in position by means of a 75 bayonet catch j' and is consequently readily removable for the substitution of a bush of different size or shape of aperture. The bayonet catch j' projects inwardly from a ring j^2 which has an inwardly turned flange 80 j^3 at its rear end acting as an abutment for the bush j and an outwardly extending flange j^4 at its front end serving as a cover plate for a ball bearing upon which the revoluble support runs. The balls k of this 85 bearing run between an outer fixed ball race k' and an inner revolving ball race k^2 , the arrangement being such that any lateral thrust, due for example to a slight irregularity in the blank, is taken by the ball 90 bearing.

In a turning operation the screw cutting die head carrying the screw cutting dies m , is unlatched and swung into the position shown in dotted lines in Figs. 1 and 2, the 95 blank rod is fed forward to a suitable extent through the lathe head and secured in the lathe chuck. The blank is then fed through the bush j to be operated on by the cutting-tools d which may all be arranged to 100 follow on if the body of the blank is to be turned down to the same diameter at all points, or may be arranged in pairs, each pair set, by means of the setting screws d' , to the same depth and cut and secured in position by the clamping screws d^2 . Upon the completion of the turning operation the turned rod is withdrawn and the screw cut-

ting die head may be swung into alinement with the tool box, and the screw cutting dies moved into operative position.

Having thus described the nature of this invention and the best means I know of carrying the same into practical effect, I claim:

1. In a lathe attachment of the character herein referred to for turning and screw-threading a metal blank, the combination of a turning tool box having a head plate, a laterally swinging screw-cutting die head pivotally attached to the head plate, and a detachable revoluble bushing interposed between the tool box and screw-cutting die head.
2. In a lathe attachment of the character herein referred to, for turning and screw-threading a metal blank, the combination of a turning tool box having a head plate, a laterally swinging screw-cutting die head pivotally attached to the head plate, a ball bearing device supported on the head plate intermediate of the tool box and screw-cutting die head, and a detachable bushing revolvably mounted in said ball bearing device.
3. In a lathe attachment of the character herein referred to for turning and screw-threading a metal blank, the combination of a turning tool box having a head plate, a

screw cutting die plate pivotally attached to the head plate and capable of swinging from a position wherein it is concentric with the tool box into a position wherein it is clear of the face of the tool box head and vice versa, and means for locking the die plate in each position.

4. In a device of the character referred to herein for turning and screw-threading a metal blank, the combination with a turning tool box and a screw cutting die head pivotally mounted thereon of a revoluble support for the blank comprising a removable bush and a ball bearing device consisting of an outer ball race fixed in the wall of the tool box, an inner revolving ball race, balls interposed between the said races, a ring member bearing on the inner ball race and detachably connected to said bush, said ring having both an inwardly turned flange serving as an abutment for the bush and an outwardly extending flange serving as a cover for the ball bearing.

In testimony whereof I have signed my name to this specification in the presence of two subscribing witnesses.

HENRY STEPHEN LAND.
